UNITED STATES PATENT OFFICE.

THEODORE KRESS, OF FORT WAYNE, INDIANA, ASSIGNOR OF ONE-TENTH TO JOHN P. KRESS,
OF FORT WAYNE, INDIANA.

ROOF.

No. 924,244.

Specification of Letters Patent. Patented June 8, 1909.

Application filed July 25, 1908. Serial No. 445,349.

To all whom it may concern:

Be it known that I, THEODORE KRESS, a citizen of the United States, residing at Fort Wayne, in the State of Indiana, have invented a new and useful Roof, of which the following is a specification.

This invention relates to roofs particularly designed for use upon railway cars although it is also capable of use upon buildings.

10 The object of the invention is to provide a metal roof made up of series of plates detachably connected in a novel manner, it being possible to readily remove any one or 15 more of the plates for the purpose of repairing or replacing them.

A further object is to provide a roof structure the parts of which when assembled will positively prevent leakage.

20 With these and other objects in view the invention consists of certain novel features of construction and combinations of parts which will be hereinafter more fully described and pointed out in the claims.

25 In the accompanying drawings is shown the preferred form of the invention.

In said drawings: Figure 1 is a plan view of a portion of a roof embodying the present improvements, one of the caps thereof being 30 removed and one of the guard strips being shifted out of its normal position. Fig. 2 is an inverted perspective view of one of the caps. Fig. 3 is a vertical section through one side portion of the roof and showing the 35 means for coupling the roof plates to the eaves. Fig. 4 is a perspective view of one of the fastening devices shown in section in Fig. 3. Fig. 5 is an end elevation of the meeting edges of two of the roof plates and 40 of the guard engaging the same.

Referring to the figures by characters of reference, 1 designates a roof plate angular in outline and provided at each side edge with an upstanding flange 2 the edge portion of which is folded as indicated at 3 to form a longitudinal lip. The plates when assembled have their flanges 2 in contact and the folded portions of the flanges are designed to be slidably engaged by an inverted longitudinally channelled guard strip 4 the longitudinal edges of which are inturned as shown at 5 so as to project into the folds of the flanges 2 and thus prevent separation of the plates 1 unless guard strip 4 is first slid longitudinally out of engagement with the 55 flanges 2. Wings 6 are formed at the adjoining ends of the strips 4 and are for the purpose hereinafter set forth. Each plate 1 has an upstanding flange 7 at its inner end and the flanges 7 of the adjoining plates are 60 designed to contact and to be straddled by an inverted channelled strip 8. The adjoining ends of these strips are flared or enlarged as indicated at 9. Downwardly directed flanges 10 are preferably formed at the outer ends of 65 the plates 1 and are folded inwardly as shown at 11 so as to engage tongues 12 which lap and are formed integral with coupling plates 13 designed to extend under the flanges 10 and to be nailed or otherwise secured to the eaves 14 of a roof. Another tongue 15 extends from each plate 13 between the tongues 12 and is designed to project under the flanges 2 of the meeting plates, there being a longitudinal groove 16 within 70 the tongue 15 and extending also within the plate 13 and which is designed to receive any moisture which might by chance enter between the flanges 2 close to the exposed or outer ends thereof. It is to be understood 75 that the roof is preferably formed of two series of plates such as herein described, the plates of the two series extending in opposite directions from the ridge of the roof. The flanges 7 are disposed along the ridge and are 80 held together by the strips 8. The flanges 2, however, extend from the ridge toward the eaves and are held together in the manner hereinbefore described. Those corners of 85 the plates 1 which are located at the ridge of the roof are bent upwardly and crimped as indicated at 17 so as to form an opening 18 therebetween through which the ridge pole 19 of the roof is exposed, there being an 90 opening 20 in the ridge pole at the center of 95 the opening 18. The wings 6 of guard strips 4 are designed to bear against the crimped portions of the plates and the enlargements 9 of the strips 8 are also designed to bear against said upstanding crimped portions. 100 These wings 6, enlargements 9, and crimped portions 17 are designed to project into a cap 21 preferably circular in form and having a central boss 22 which projects into the opening 18 and has a screw threaded passage 23 105 for the reception of a bolt 24. Arms 25 extend radially from the cap 21 and have longitudinal channels 26 and these arms are so positioned that when the cap is placed upon the upstanding corrugated portions 17 the 110

arms 25 will straddle the strips 4 and 8 while the wings 6 and the enlargements 7 will be seated within the cap. The plates thus engaged, together with the strips 4 and 8 engaging them will thus be prevented from pulling apart.

A saddle strip 27 is preferably arranged diametrically upon each of the caps 21 and is channeled longitudinally as indicated at 28 10 so as to receive two oppositely extending arms 25 and to fit snugly upon the strips 4. Bolt 24 is designed to extend through this saddle strip and the cap 21 and into opening 20 in the ridge pole and said bolt can be secured in any suitable manner as by nuts. Those ends of the plates 1 disposed above the eaves have their flanges 10 interlocking with the tongues 12 of plates 13 which plates are secured to the eaves and have their tongues 15 extending under the flanges 2 of the adjoining plates.

Those of the plates 1 located at the ends of the roof are each provided with only one flange 2, the other or opposite edge of the plate being bent downward so as to lap the 25 ends of the roof. Moreover, those of the strips 8 which engage the flanges 7 of the end plates are provided at their outer ends with cap plates 29, which plates are integral with the strips 8 and are designed to close the 30 space between the ends of flanges 7 and between the meeting portions of the plates 1. Although the roof has been described as consisting of two series of plates each plate being 35 provided with flanges 2, 7 and 10 such as herein described it is to be understood that in very large roofs more than one plate may be disposed between the ridge and the eave of the roof, said plates being secured 40 together in any suitable manner as by soldering them.

Whenever it is desired to remove one or more plates from the roof, saddle strips 27 and the cap 21 engaging said plate are removed and the proper strips 4 are then shifted longitudinally out of engagement 45 with flanges 2. The channeled strips 8 are then lifted from the flanges 7 and the plate 13 detached from the eave. The plate 1 to 50 be removed can thus be lifted out of position and by reversing the foregoing operation another plate can be substituted therefor.

What is claimed is:

1. In a roof structure the combination 55 with plates having contacting longitudinally folded flanges; of an inverted channeled guard strip straddling said flanges and having inturned edge portions interlocking therewith, laterally diverging wings integral with 60 each strip, and means for engaging the wings to hold them against movement relative to the plates.

2. In a roof structure the combination 65 with oppositely disposed series of plates having contacting flanges, means for binding the

flanges together, said plates having diagonally disposed upstanding corner portions; of means for housing said upstanding portions to hold the plates together, and means extending between said diagonally disposed upstanding portions for securing said housing means to a roof beam.

3. In a roof structure the combination with series of oppositely disposed contacting plates, said plates having outstanding flanges, 75 and means straddling the flanges for holding the plates together, said plates having upstanding crimped portions at their adjoining corners; of a cap inclosing said upstanding portions and engaging said straddling means, 80 and means for securing the cap in position.

4. A roof structure comprising series of oppositely extending contacting plates, the plates of the two series being in contact, there being outstanding flanges at the meeting edges of the plates, means straddling the contacting flanges for holding the plates together, said plates having diagonally disposed upstanding corner portions, diverging wings upon said means for straddling the 85 corner portions and a cap inclosing said upstanding portions and wings and engaging said means for holding the plates and straddling means together.

5. A roof structure comprising series of 95 oppositely extending contacting plates, the plates of the two series being disposed in contact, there being outstanding flanges at the adjoining edges of the plates, channeled members straddling the adjoining flanges, 100 said members having enlarged end portions, and means detachably secured upon the plates for engaging said end portions.

6. A roof structure comprising series of 105 oppositely extending contacting plates, the plates of the two series being disposed in contact, outstanding flanges upon the contacting portions of the plates, means straddling said flanges for holding the plates together, said plates being provided at their 110 meeting corners with obliquely disposed upstanding portions, and a cap housing said corner portions and engaging the adjoining portions of the straddling means.

7. A roof structure comprising series of 115 oppositely extending contacting plates, the plates of the two series being disposed in contact, outstanding flanges upon the contacting portions of the plates, means straddling said flanges for holding the plates together, the meeting corners of said plates being provided with obliquely disposed upstanding portions, a cap housing said corner portions and engaging the adjoining portions of the straddling means, a saddle strip 120 mounted upon the cap and engaging opposite straddling means, and means for securing the saddle strip and cap to a roof beam.

8. A roof structure comprising contacting plates having their meeting corners provided 130

with obliquely disposed upstanding portions, and a cap extending over and housing said upstanding portions for holding the plates together.

5 9. A roof structure comprising contacting plates having their meeting corners provided with obliquely disposed upstanding portions, and a cap extending over and housing said upstanding portions for holding the plates together, a saddle strip extending over the cap and engaging the plates thereunder, and means extending through the saddle strip and cap for securing it to a roof beam.

10 10. A roof structure comprising plates having upstanding edge portions, the adjoining corners of said plates being spaced apart and having obliquely disposed upstanding portions, a cap extending over and housing said upstanding corner portions, said cap having channeled arms embracing the upstanding edge portions of the adjoining plates, and means for securing the cap upon the plates.

11. A roof structure comprising contacting plates having their adjoining corner portions upstanding therefrom along obliquely extending lines to form an opening there-

between, said plates being provided with contacting edge flanges, a cap extending over and housing the upstanding corner portions, said cap having radial arms embracing the edge flanges, and means extending through the cap and the opening between the corners for securing the cap upon the plates. 35

12. In a roof structure the combination with roof plates having depending folded edge flanges at one end and upstanding contacting flanges at their adjoining edges; of a coupling plate extending under the depending flanges, said plate having tongues upon one face thereof and lapsing the plate for engagement with the folded depending flanges of the roof plates, there being a tongue extending from the coupling plate and under 45 the meeting edges of the roof plates, said last mentioned tongue and the corner plate having a drain channel.

In testimony that I claim the foregoing as my own, I have hereto affixed my signature in the presence of two witnesses.
